UNITED STATES PATENT OFFICE.

WALTER J. BAKER, OF CHICAGO, ILLINOIS.

DESIGN FOR A CABINET FOR PHONOGRAHPS.

50,641.

Specification for Design.

Patented Apr. 17, 1917.

Application filed March 6, 1917. Serial No. 152,941. Term of patent 3½ years.

To all whom it may concern:

Be it known that I, WALTER J. BAKER, a citizen of the United States, residing at Chicago, in the county of Cook and State of Illinois, have invented a new, original, and ornamental Design for a Cabinet for Phonographs, of which the following is a specification, reference being had to the accompanying drawing, forming part thereof.

The figure is a view in perspective of a cabinet for phonographs, showing my new design.

I claim:

The ornamental design for a cabinet for phonographs, as shown.

WALTER J. BAKER.
